SPACER FOR PLUMBING FIXTURES
 Otto J. Litzkow, Chippewa Falls, Wis.
 Filed Apr. 28, 1961, Ser. No. 106,379
 11 Claims. (Cl. 4—252)

This invention relates to plumbing and consists of a device to improve the installation of wall supported closet bowls.

It is essential to the installation of most wall supported closet bowls that a minimum space of approximately $\frac{1}{16}$ inch exist between the wall and the attached closet bowl. If the bowl touches the wall at any point when the retaining nuts are tightened during installation, or during subsequent use, the vitreous china of the bowl will crack or break. Methods heretofore used to adjust the position of the support bolt nuts and washers which determine the spacing for the bowl have been time consuming and unreliable. It is, therefore, a primary object of my invention to provide a closet bowl spacer which will make possible the quick and accurate installation of a wall supported closet bowl.

It is a further object of my invention to provide a closet bowl spacer which will prevent breakage of wall supported closet bowl due to improper installation.

Other objects and advantages will be apparent from the following detailed explanation taken in conjunction with the accompanying drawings wherein a preferred embodiment of the principles of the invention has been selected for exemplification.

In the drawings:

FIG. 1 is a perspective view of my invention in use.

FIG. 2 is a partial section view of my invention taken along section line 2—2 of FIG. 1.

FIG. 3 is a partial side view of a closet bowl which has been installed with the aid of my invention, with broken out sections showing the wall.

FIG. 4 is a partial section view taken along line 4—4 of FIG. 1 showing the relation of a spacer bolt and a spacer hole of my invention.

My closet bowl spacer has a rigid frame 6 with an inner face 7, which must be substantially flat so as to permit positioning of the frame 6 substantially parallel to the outer surface 17 of the wall 16 as shown in FIGS. 2 and 4. The frame 6 may be made of any suitable material as long as it will remain rigid and flat. A handle 21 is preferably attached to the spacer frame 6 as shown in FIGS. 1 and 2 to facilitate the handling and use of the frame, and also to aid in aligning the waste pipe 23, which extends through the frame center opening 24.

Adjustment holes 8 are located at various positions in the frame 6 to correspond to the spacing of the support bolts 5 for the various models of closet bowls 13 which are to be installed. FIG. 1 shows my spacer frame 6 being used with a typical installation consisting of four support bolts 5. It will be noted that the adjustment holes 8 may be round 8a or slotted 8b for ease of positioning. Closet bowls supported by only three support bolts are also common and suitable adjustment holes 8 are shown provided in the spacer frame 6 to accommodate the installation of those bowls also.

At several points on the inner face 7 of my spacer frame 6 the spacing heads 10 of spacer bolts 9 protrude an equal distance x as shown in FIGS. 2 and 4. It can be seen that a recess 13 is provided in the spacer frame 6 to receive each spacer bolt spacing head 10. Distance x is the width of the substantially uniform space which is required between the installed closet bowl 22 and the outside surface 17 of the wall 16, as shown in FIG. 3. The purpose of the space is to prevent the bowl from touching the wall during installation or use which would

2

cause the bowl to break. The distance x may vary somewhat, depending on the model of closet bowl which is being installed, but a normal minimum value is approximately $\frac{1}{16}$ inch. It is very important that the spacing head 10 of every spacer bolt 9 extend an equal distance x from the inner face 7 to insure correct alignment of the installed closet bowl. The spacer bolts 9 may be firmly fixed to the spacer frame 6 or they may be engaged in threaded relation by spacer holes 12, as shown in FIG. 4, with lock nuts 11 maintaining the spacer bolts in the desired position.

Accurate alignment of a wall supported closet bowl 22 is extremely quick and easy, using my spacer frame. First, the support bolt nuts 19 and washers 20 are placed within the wall indentures 18 on the support bolts 5, as shown in FIG. 2. Then the spacer frame 6 is positioned so that the inner face 7 is facing the wall 16 and the support bolts 5 pass through the appropriate adjustment holes 8, with the spacing heads 10 of the spacer bolts 9 in abutment with the outside wall surface 17. The support bolt nuts 19 and washers 20 are then adjusted so that each washer 20 is held flush with the inner face 7 of the spacer frame by nut 19, maintaining the abutting relation of the spacer bolt spacing heads 10 and the outside wall surface 17. The support bolt nuts 19 and washers 20 are then in perfect adjustment and the spacer frame 6 may be slipped off the support bolts 5. To complete the installation, the closet bowl 22 is merely slipped on the support bolts until it abuts the support bolt washers 20, and the retaining washer 15 and the retaining nut 14 are tightened in place, as illustrated in FIG. 4.

The foregoing description clearly indicates the advantage of using my spacer frame to attain perfect alignment of wall supported closet bowls. It is no longer necessary to lift the heavy bowl onto the support bolts to measure the space width x and then lift the bowl back off to allow adjustment of the support bolt nuts and washers, followed by another awkward measuring operation and further adjustment, repeated several times, until space x appears correct. With the old method, it was extremely difficult to detect whether one support nut and washer were out of alignment, with the result that breakage during installation and subsequent use was not uncommon. With my light spacer frame 6, any misalignment of a support nut 20 and washer 19, or non-uniform spacing between the inner face 7 and the wall 16, are immediately apparent. Correction of the misalignment is quick and easy, and the subsequent alignment of the closet bowl is always accurate.

A possible low cost modification of my invention would be a spacer frame 6 with fixed spacer bolts 9 having spacing heads 10 extending a fixed equal distance x from the inside face 7 of the frame 6.

It is understood that the present invention is not confined to the particular construction and arrangement of parts herein illustrated and described, but embraces all such modified forms thereof as may come within the scope of the following claims.

I claim:

- 60 1. A spacer for a wall supported closet bowl comprising, a rigid frame having an inner face and a center opening adapted to allow the waste pipe for said closet bowl to extend therethrough, a plurality of adjustment holes located at spaced intervals in said frame, a plurality of spacer bolts having spacing heads which extend a substantially equal distance beyond said inner face of said frame.
- 65 2. The invention described in claim 1 wherein the portions of said inner face surrounding said adjustment holes and said spacer bolts are in substantially coplanar relation.
- 70 3. In combination, support bolts for a wall supported closet bowl, each of said support bolts having a nut and

washer attached in adjustable relation, a rigid spacer frame having a substantially flat inner face and a center opening adapted to allow the waste pipe for said closet bowl to extend therethrough, a plurality of adjustment holes located at spaced intervals in said frame, said adjustment holes encompassing said support bolts in free relation, a plurality of spacer bolts having spacing heads which extend beyond said inner face of said frame a substantially equal distance and abut said wall, said washers being retained in abutment with said inner face by said nuts.

4. A spacer for a wall supported closet bowl comprising, a rigid frame with a substantially flat inner face and having a plurality of spacer holes, spacer bolts carried by said spacer holes, said spacer bolts having spacing heads which extend beyond said inner face of said frame a substantially equal distance, a plurality of adjustment holes located at spaced intervals in said frame, and a center opening in said frame adapted to allow the waste pipe for said closet bowl to extend therethrough.

5. A spacer for a wall supported closet bowl comprising, a rigid frame with an inner face, a plurality of adjustment holes located at spaced intervals in said frame, a plurality of spacer bolts having spacing heads which extend a substantially equal distance beyond said inner face of said frame, said spacer bolts having locking means and being carried in adjustable relation with said frame by spacer holes to permit changing the distance said spacing heads extend beyond said frame inner face, said spacing heads being located partially within recesses in said frame inner face.

6. A spacer for a wall supported closet bowl comprising, a rigid frame with an inner face, a plurality of slotted adjustment holes located at spaced intervals in said frame, a plurality of spacer bolts having spacing heads which extend a substantially equal distance beyond said inner face of said frame.

7. A spacer for a wall supported closet bowl comprising, a rigid frame with an inner face, a plurality of adjustment holes located at spaced intervals in said frame, a plurality of spacer bolts having spacing heads which extend a substantially equal distance beyond said inner face of said frame, and a handle attached to said frame.

8. In combination, support bolts for a wall supported closet bowl, each of said support bolts having a nut and washer attached in adjustable relation, a rigid spacer

frame having a substantially flat inner face, a plurality of adjustment holes located at spaced intervals in said frame, said adjustment holes encompassing said support bolts in free relation, a plurality of spacer bolts having spacing heads which extend beyond said inner face of said frame a substantially equal distance and abut said wall, said spacer bolts having locking means and being carried in adjustable relation with said frame by spacer holes to permit changing the distance said spacing heads extend beyond said inner face, said spacing heads being located partially within recesses in said inner faces.

9. In combination, support bolts for a wall supported closet bowl, each of said support bolts having a nut and washer attached in adjustable relation, a rigid spacer frame having a substantially flat inner face, a plurality of slotted adjustment holes located at spaced intervals in said frame, said adjustment holes encompassing said support bolts in free relation, a plurality of spacer bolts having spacing heads which extend beyond said inner face of said frame a substantially equal distance and abut said wall, said washers being retained in abutment with said inner face by said nuts.

10. A spacer for a wall supported closet bowl comprising, a rigid frame with a substantially flat inner face and having a plurality of spacer holes, spacer bolts carried by said spacer holes, said spacer bolts having spacing heads which extend beyond said inner face of said frame a substantially equal distance, said spacer bolts having locking means and being carried in adjustable relation by said spacer holes to permit changing the distance said spacing heads extend beyond said inner face, said spacing heads being carried partially within recesses in said inner frame inner face, a plurality of adjustment holes located at spaced intervals in said frame.

11. A spacer for a wall supported closet bowl comprising, a rigid frame with a substantially flat inner face and having a plurality of spacer holes, spacer bolts carried by said spacer holes, said spacer bolts having spacing heads which extend beyond said inner face of said frame a substantially equal distance, a plurality of slotted adjustment holes located at spaced intervals in said frame.
